DESIGN FOR A PAIR OF SPECTACLES

William R. Uhlemann, Evanston, Ill., assignor to Uhlemann Optical Company of Illinois, Chicago, Ill., a corporation of Delaware

Application June 23, 1938, Serial No. 78,008

Term of patent 14 years

To all whom it may concern:

Be it known that I, William R. Uhlemann, a citizen of the United States, residing at 581 Ingleside Park, Evanston, Illinois, in the county of Cook and State of Illinois, have invented a new, original, and ornamental Design for a Pair of Spectacles, of which the following is a specification, reference being made to the accompanying drawing, forming a part thereof.

Fig. 1 is a front elevational view of a pair of spectacles showing my new design;

Fig. 2 is a top plan view;

Fig. 3 is a fragmentary end view from the outside;

Fig. 4 is a fragmentary perspective view from the nasal side; and

Fig. 5 is a fragmentary perspective view from the outside.

The temples have been shown in a fragmentary condition in Figs. 2, 3, and 5 for convenience of illustration; and Figs. 3, 4, and 5 are on an enlarged scale.

The characteristic features of the design are shown in full lines in the drawing.

I claim:

The ornamental design for a pair of spectacles, substantially as shown and described.

WILLIAM R. UHLEMANN.
